(57) **CLAIM**

The ornamental design for a dishwasher rack assembly, as shown and described.

DESCRIPTION

FIG. 1 is a top perspective view of a dishwasher rack assembly showing my new design;

FIG. 2 is a bottom perspective view thereof;

FIG. 3 is a front view thereof;

FIG. 4 is rear side view thereof;

FIG. 5 is a left side view thereof;

FIG. 6 is a right side view thereof;

FIG. 7 is a top view thereof; and

FIG. 8 is a bottom view thereof.

FIG. 9 is a top perspective view of the dishwasher rack and sprayer only from FIG. 1.

FIG. 10 is a bottom perspective view thereof;

FIG. 11 is a left side view thereof;

FIG. 12 is a right side view thereof;

FIG. 13 is a top view thereof; and

FIG. 14 is a bottom view thereof.

FIG. 15 is a front perspective view of the sprayer assembly only shown in a disassemble state from FIG. 1.

FIG. 16 is a bottom perspective view thereof;

(Continued)

FIG. 17 is a front view thereof;
 FIG. 18 is a rear view thereof;
 FIG. 19 is a left side view thereof;
 FIG. 20 is a right side view thereof;
 FIG. 21 is a top view thereof;
 FIG. 22 is a bottom view thereof;
 FIG. 23 is a front perspective view of the wicking element only shown in a disassembled state from FIG. 1.
 FIG. 24 is a bottom perspective view thereof;
 FIG. 25 is a top view thereof;
 FIG. 26 is a bottom view thereof;
 FIG. 27 is a left side view thereof;
 FIG. 28 is a right side view thereof;
 FIG. 29 is a front view thereof; and,
 FIG. 30 is a rear view thereof.
 The broken lines showing portions of the dishwasher rack assembly form no part of the claimed design.
